Claims priority, application France June 30, 1956

4 Claims. (Cl. 60—67)

In steam turbine installations, the condensed water is usually reheated in a series of water reheaters consisting of tubular heat exchangers fed by steam drawn off from the turbine. The heat given up in such a reheat by the steam drawn off, between the temperature at which it leaves the turbine and a temperature equal to or slightly higher than, the saturation temperature corresponding to its pressure, that is to say the reheating heat of the reheat, is given up to the water in a particular zone known as the "de-superheating" zone, which precedes, in the direction of flow of the steam, the so-called "saturated" zone, where the steam gives up its latent heat of vaporisation.

In such an installation, the heat exchange in the de-superheating zone introduces an element of irreversibility into the thermodynamic cycle because the temperature of the steam may be much higher than that of the water, especially in installations comprising one or more re-superheating operations.

The present invention has the purpose of increasing the efficiency of the installation by reducing the degree of irreversibility in the thermodynamic cycle.

According to the invention, the installation is characterised by the fact that it comprises means for sampling a fractional delivery of water in at least one condensed water reheat at the point where the water has finished reheating in the saturated steam zone of the reheat, a heat-exchanger being provided in order to reheat the said fractional delivery of water to a temperature slightly lower than that of the steam drawn off from the turbine, and means being finally provided to re-introduce the said fractional delivery into the main water circuit, the point of re-introduction being situated after the first water reheat in the direction of flow, reckoning from the output of the reheat set, whereof the output temperature is lower than the temperature of the fractional delivery of reheated water.

The delivery of water drawn off can, in certain cases, be divided into two parts after a predetermined degree of reheating, one of the said parts continuing alone to be reheated, the two parts being re-introduced into the main water circuit at two separate points suitably chosen as a function of the respective final temperatures of the two parts.

An installation according to the invention is diagrammatically illustrated in the attached drawing, and described hereinafter.

In the drawing:

Figure 1 is an overall diagram of the installation.

Figure 2 is a diagram of the temperatures in an installation as shown in Figure 1.

Figure 3 is a partial diagram showing a subdivided water take-off.

Figure 4 is a diagram of the temperatures in an installation wherein the water drawn off is partially vaporised.

Figures 5 and 6 show two types of water reheaters incorporating the heat-exchangers used.

2

Figure 7 shows a variant of an embodiment of the installation in the case where the water reheat is of the mixer type.

Figure 8 is a modification of Figure 1.

5 The diagram in Figure 1 shows an initial water sampling system in the case of a re-superheating turbine, for which only three steam take-offs are illustrated.

In this diagram, 1 designates the high-pressure part of the turbine, 2 the re-superheater, 3 the lower pressure turbine, and 4 the condenser. Three condensed water reheaters 5, 6 and 7 are fed by the three steam take-offs 8, 9 and 10 respectively. The saturated zones of these reheaters are designated by 5a, 6a and 7a respectively, while the de-superheating zones are designated 15 by 5b, 6b and 7b. The condensed water outlets of the reheaters are illustrated at 8a, 9a and 10a.

The reheat 5 is fed by water from condenser 4 through conduit 14 to reheat 5a comprises a water take-off 11 which is reheated by the take-off 8 in the 20 zone 5b, the heat-exchanger used replacing, in this zone, the usual de-superheating exchanger for the steam drawn off.

The delivery of reheated water 11 is conveyed at 12 to the main water delivery 14c at the outlet of the last 25 reheat if its temperature is higher than that of the water at the outlet of the reheating set of the turbine.

In the opposite case, the delivery of reheated water 11 is conveyed at 13 in Figure 8 to the condensed water circuit 14b after the first reheat, reckoning from the 30 outlet of the reheating set, for example 6, whereof the outlet temperature is lower than its own temperature. Water from reheat 5a is taken by conduit 14a to reheat 6a, then through reheat 6b and, by conduit 14b, to heaters 7a and 7b to water delivery conduit 14c.

35 The water take-offs are contrived in the same fashion on each of the other reheaters; they are not illustrated for the sake of clarity in the diagram.

In the diagram in Figure 2, wherein the quantities of heat exchanged are plotted as abscissae, and the temperatures as ordinates, the curves T and t respectively represent the variation of steam and water temperature as a function of the quantity of heat exchanged in unit time. The two curves T and t are of the shape shown 40 because the specific heat of water is an increasing function of temperature, and the specific heat of steam on the other hand is a decreasing function of temperature.

The point A represents the temperature of the steam and the point G the temperature of the water at the end of the de-superheating zone. The horizontal line sS represents the saturation temperature corresponding to the 45 steam pressure in the saturated zone, and the curve gG represents the end of water temperature variation in the said zone. The point A may possibly coincide with the point S, or be situated slightly above the point S, according to the surface area of the de-superheating exchanger. The interval SG is generally of the order of 2 to 3° C. in an ordinary reheat.

The improvement obtained in the efficiency of the installation becomes greater as the two curves T and t 50 approach one another, and consequently as the delivery of water drawn off becomes smaller, but the said delivery must be fixed by a diaphragm or valve (not illustrated), in such a manner that:

(a) there is always sufficient difference in temperature 55 between the steam and the water. Since the interval AG is small, this condition is realised if the slope of the curve t is not greater than that of the curve T at the points G and A respectively.

(b) the difference in temperature at the end of the 60 heat-exchanger where the fluids are hottest, represented by BC, remains sufficiently large for the area of the heat-exchanger not to make this appliance too costly.

In the case in which the condition (a) is determinative, the efficiency of the cycle may be increased by bypassing from the delivery of water drawn off, during re-heating, a partial delivery which continues to be reheated alone in accordance with the curve D; the result of this is a reduction in the final temperature difference, which becomes BE instead of BC.

This divided take-off, which forms a supplementary feature of the invention, is illustrated in the diagram in Figure 3.

In this diagram, 8 is the steam take-off, 14 is the main water delivery, 15 is the delivery of water drawn off, which divides, after having been subjected to a first re-heating operation, into a delivery 11 which is returned to the circuit at a point chosen in accordance with the foregoing, for example before one of the subsequent re-heaters, and a delivery 16 which continues to be reheated, and is then returned to the circuit at another suitably chosen point, for example at the outlet of the last re-heater.

The efficiency of the cycle could be further increased by bypassing, from the delivery of water drawn off, a second amount, which would be reheated in accordance with the curve d in the diagram in Figure 2, the final difference in temperature then being represented by BF, and so forth.

The water take-offs do not require any pump other than the pumps normally provided in a steam turbine installation in the case of water reheaters of the so-called "high-pressure" type, that is to say situated on the delivery side of the pump feeding the steam generator. In fact, in this case, the water drawn off only has to pass through the exchanger which re-heats it, while the main water delivery has to pass through the subsequent water reheaters, which are at least one in number. There is therefore enough pressure available to ensure circulation of the delivery drawn off.

On the other hand, a special pump is required in the case of low-pressure reheaters situated before the feed pump, if the delivery of water drawn off must be conveyed to the high-pressure circuit. However, in order to avoid having to install a low-power high-pressure pump, the delivery of water drawn off may be conveyed to the body of the re-heater provided itself, where it mixes with the blow-offs coming from the higher-pressure re-heaters, instead of being conveyed to the main water delivery before it enters the re-heater. The two processes are in fact substantially equivalent as regards efficiency.

In certain cases, the temperature at which the steam is drawn off may be sufficiently high for the delivery of water drawn off to be partially vaporised. The temperatures then vary as shown in the diagram in Figure 4, wherein the curve T represents steam temperature, and the curve t represents water temperature, this latter curve having a horizontal portion HI during which the water becomes partially vaporised. Then either the delivery of water drawn off may be increased in order to prevent vaporisation, the temperature then varying in accordance with GK, or partial vaporisation in accordance with HI may be accepted, which increases the efficiency in so far as the condition (a) defined above does not cause any limitation in this method. The heat-exchanger then comprises a zone where partial vaporisation occurs, and the tubes must be so shaped in this zone that the steam cannot accumulate at a bend and hinder circulation.

It is then advantageous to convey the mixture of water and steam leaving the exchanger either to the container of the steam generator if the temperature of the said mixture is higher than that of the saturated steam in the last re-heater, or, in the opposite case, to the saturated zone of the first re-heater for which the steam temperature is higher than that of the mixture.

All kinds of construction of water re-heaters can be used for putting the invention into practice.

Figures 5 and 6 show, in more or less diagrammatic form, and by way of example, two water re-heaters with heat exchanger incorporated for reheating the delivery of water drawn off.

The exchanger illustrated in Figure 5 is of the water-box type, and that in Figure 6 of the header type.

In these two figures, 21 and 22 respectively designate the saturated zone and the heat-exchanger incorporated in order to reheat the water drawn off, while 23 and 24 respectively designate the steam inlet and the condensed water outlet.

In the re-heater shown in Figure 5, the water enters at 25, the main water delivery outlet is situated at 26, and th outlet for the water drawn off at 27.

The re-heater shown in Figure 6 comprises a water inlet header 28, an intermediate header 29 and an outlet header 30 for the water drawn off.

If the water re-heater is of the mixer type, which is so in the case of a degasifier, the delivery of water drawn off can be reheated in a special exchanger. The diagram of such an exchanger is shown in Figure 7, wherein 8 is the steam take-off, 14 the main water delivery, 11 the delivery of water drawn off, 19 the pump which aspirates the water leaving the re-heater, and 20 the special exchanger.

What is claimed is:

1. In a steam turbine installation including a turbine and a turbine condenser, a plurality of feedwater heaters, a first steam zone and a second steam zone for each of said heaters, a steam path from the turbine to said first zone and then to said second zone for each of said heaters, a feedwater path from the turbine condenser to said second zone of the first of said heaters, a tap in said first heater between said zones of said first heater dividing the reheated feedwater when the feedwater has been heated in said second steam zone of said first heater, a part of the feedwater passing through said first steam zone of said first heater for heating to a temperature less than but approximating that of the steam from the turbine, the remainder of the feedwater passing from said tap to said second steam zone of an adjacent one of said heaters and then passing in series through said second and then said first zones of the remainder of said heaters and said part of the feedwater after heating in said first zone of said first heater entering the feedwater path downstream of the adjacent one of said feedwater heaters to said first feedwater heater.

2. In an installation as described in claim 1, a tap in said first steam zone of said first heater dividing the feedwater heated in said first steam zone into two parts one of which is further heated in said first steam zone, said two feedwater parts being reintroduced into the feedwater path downstream of the adjacent one of said feedwater heaters to said first feedwater heater.

3. In an installation as described in claim 2, said further heated parts of said two parts of said feedwater being introduced into the feedwater path at a point after the last of said heaters in the direction of feedwater flow.

4. An installation as described in claim 1 in which each of said heaters is a tubular heat exchanger having a first steam zone and a second steam zone.
